UNITED STATES PATENT OFFICE

WILLIAM C. McWHIRTER, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY SWITCH OPERATING APPARATUS

Application filed March 18, 1930. Serial No. 436,718.

My invention relates to railway switch operating apparatus, and has for an object the provision of a buffering device for a spring switch which will permit free movement of the switch from one extreme position to the other by a switch operating device, and which will permit the switch points to be freely moved away from either extreme position by a trailing vehicle, but which will retard the return of the switch points to their initial positions after such vehicle has trailed through the switch.

I will describe one form of apparatus embodying my invention, and will then point out the novel features thereof in claims.

In the accompanying drawings, Fig. 1 is a top plan view, partly cross-sectioned, showing one form of apparatus embodying my invention. Fig. 2 is an enlarged sectional view on the line II—II of Fig. 1. Fig. 3 is an enlarged sectional view on the line III—III of Fig. 1. Fig. 4 is an enlarged fragmental sectional view on the line IV—IV of Fig. 3. Fig. 5 is an enlarged sectional view on the line V—V of Fig. 1.

Similar reference characters refer to similar parts in each of the several views.

Referring first to Fig. 1, the reference character A designates a railway switch, and the reference character B designates a device for operating it. The switch A comprises, as usual, two fixed rails 1 and 1^a, and two movable switch points 2 and 2^a, the switch points being connected together near their tips by a front rod 3.

The operating device B, as here shown, comprises a switch stand 14 having its base 15 spiked or otherwise secured to the ties adjacent the switch A. A vertical shaft 16, journaled in the switch stand 14, carries a crank 21 and a gear segment 17. The gear segment 17 meshes with a bevel pinion 18 keyed to a pinion shaft 19. The pinion shaft 19 extends through the side of the switch stand 14 and has attached to its outer end the usual weighted switch-throwing lever 20.

The crank 21 of the switch stand 14 is operatively connected with the front rod 3 of the switch A by means of a link 13^a and a spring connecting rod C. The spring con-

necting rod C may have any suitable form, but in the well known form here shown, this connecting rod comprises a cylindrical housing 10 having a lateral extension 10^b attached to a bar 13 which is pivotally attached to the link 13^a. The left-hand end 10^a of the housing 10 has a smaller diameter than the body of the housing, while the right-hand end is threaded to receive a cap 11 having an end 11^a similar to the end 10^a. Slidably mounted in the opening in the end 10^a is a sleeve 8 provided with an annular flange 8^a located within the housing 10, and similarly mounted in the opening in the end 11^a is a sleeve 22 provided with an annular flange 22^a, also located within the housing 10. A spring rod 7 extends through both sleeves with sufficient clearance to permit the rod to slide freely in the sleeves, and this rod carries a compression spring 12 which engages the sleeves at the annular flanges and urges the sleeves toward the positions in which the annular flange 8^a of the sleeve 8 engages the shoulder formed on the inside of the housing by the end 10^a, and the annular flange 22^a of the sleeve 22 engages the shoulder formed on the inside of the cap 11 by the end 11^a. Both ends of the spring rod are threaded and the left-hand end is provided with two nuts 23, while the right-hand end of the rod is provided with a jam nut 6^a and a screw jaw 6. The screw jaw 6 is pivotally attached to the front rod 3.

The apparatus thus far described is well known in the art and its operation will be readily understood from an inspection of the drawings.

Associated with the spring connecting rod C is a buffering device D which, in the form here shown, comprises a casing 35 having a cylinder 35^a extending therethrough, as best seen in Fig. 3. One end of the cylinder 35^a is closed by a cylinder head 36 and the other end is closed by a cylinder head 37. A piston rod 39 extends into the cylinder 35^a through a stuffing box 37^a and through a suitable hole 37^b in the cylinder head 37, and is attached, at its inner end, to a reciprocable piston 38 by means of a castle nut 40. The piston 38 is provided with an annular groove 38^b and

with a plurality of holes 38^a which are arranged in a circle about the piston, and which communicate with the groove 38^b for at times permitting the passage of fluid through the 5 piston as will be explained more fully hereinafter. The side of the groove 38^b adjacent the holes 38^a is finished to form a valve seat, and constantly urged against this valve seat by means of a coil spring 44, is an annular 10 valve 41 having an annular flange 41^a which fits within the adjacent end of the spring 44 to hold the valve in its proper position.

The cylinder wall is provided at its left-hand end with a leak groove 35^b which permits fluid to flow past the piston 38 under certain conditions as will be made clear hereinafter.

Located in the casing 35 above the cylinder 35^a is a reservoir 43 which is constantly 20 connected with the cylinder 35^a on the right-hand side of piston 38 through a port 42. The reservoir 43 is also constantly connected with the cylinder 35^a on the left-hand side of piston 38, through a port 49 in the reservoir 25 wall and a passage in the cylinder head 36. As here shown, the passage in the cylinder head 36 comprises two ports 48 and 49, a regulating valve 47, which I will describe 30 presently, being interposed between these ports to control the flow of fluid through the ports. The reservoir 43 and cylinder 35^a are both intended to be filled with a suitable 35 fluid such as oil, and in order to permit the insertion of fluid into the reservoir and the cylinder, the reservoir wall is provided with a hole 45^a which is normally closed by a screw plug 45.

The regulating valve 47 may have any suitable form but, in the form here shown, 40 this valve comprises a cylindrical valve member 47^c (see Fig. 4) fitting in a hole 55 in the cylinder head 36, and attached to a valve stem 47^d. The valve member 47^c is provided with a plurality of restricted orifices 47^a 45 of different sizes which extend through its side in radial spaced relation and any one of which may be brought into registration with the port 48 by turning the valve member 47^c. To facilitate turning the valve member 47^c, 50 the valve stem 47^d is provided, at its upper end, with a saw kerf 47^b adapted to receive the end of a screw driver. The valve is held in place in the hole 55 in the cylinder head 36 by a gland 52 which surrounds the valve stem 47^d, and which is fastened to the cylinder head 36 by means of two stud bolts 51, each of which passes through a hole 52^b in a lug 52^a integral with the gland 52, and each of which is screwed into a suitable 55 threaded hole in the cylinder head 36. Suitable packing 54 is inserted between the gland 52 and the shoulder formed at the top of the valve member 47^c; and between the bottom of the gland and the cylinder head 36 to prevent 60 fluid from leaking past the valve.

The buffing device D is operatively connected with the spring connecting rod C in the following manner: A recess 28 is provided in one of the ties adjacent the connecting rod C, and fastened to this tie within 70 this recess in any convenient manner is a rectangular plate 25 carrying an upstanding post 24, as best seen in Fig. 2. Pivoted at one end on this post are two oppositely disposed links 26 and 27. The link 26 comprises two 75 straps 26^a and 26^b secured together by rivets 26^d but spaced from each other by spacing members 26^c and, in a similar manner, the link 27 comprises two straps 27^a and 27^b secured together by rivets 27^d but spaced from 80 each other by spacing members 27^c. The free end of the strap 26^a is offset to form a jaw, and pivoted intermediate its ends on a pin 29 which passes through this jaw is a fulcrum 85 bar 30. One end of fulcrum bar 30 is pivotally connected with the cylinder head 36 of buffing device D by means of a pin 56 which extends through the bar and through two lugs 36^a integral with the cylinder head 36. The other end of the bar 30 is pivotally connected 90 with the sleeve 8 of the connecting rod C by means of two trunnions 9^a and 9^b which are formed on a nut 9 screwed onto the end of the sleeve 8 of the resilient connecting rod C. These trunnions extend through aligned holes 95 in the bar 30, and in a member 30^a riveted to the bar 30, as best seen in Fig. 5. The free end of the strap 27^a is also offset to form a 100 jaw, and pivoted intermediate its ends on a pin 31 which passes through this jaw is a fulcrum bar 32. The fulcrum bar 32 is similar to the fulcrum bar 30, and is pivotally attached at one end to the piston rod 39 of the buffing device D by means of a screw jaw 50. The other end of the fulcrum bar 32 is 105 pivotally attached to the sleeve 22 of the spring connecting rod C by means of two trunnions which pass through aligned holes in the bar 32 and in a member 32^a riveted to the bar 32. These trunnions are formed on a nut 110 which is not shown in the drawings but which is similar to the nut 9 screwed onto the sleeve 8. In order to assist in supporting the weight of the buffing device D, a plate 34 is 115 inserted between the bar 30 and the tie, and a similar plate 33 is inserted between the bar 32 and the tie. These plates may be fastened to the tie in any convenient manner.

The operation of the apparatus as a whole 120 is as follows: When switch A occupies the extreme position in which it is shown in the drawings, the parts of buffing device D occupy the positions in which they are illustrated in Fig. 3, that is to say, piston 38 is at the left-hand end of cylinder 35^a, and valve 41 is held closed by spring 44. If, now, it is desired to reverse switch A, switch throwing lever 20 is rotated through an angle of 180° from the position in which it is illustrated in the drawings, thereby rotating gear 125 130

segment 17 and crank 21 in a counter-clockwise direction and, hence, moving bar 13 of connecting rod C toward the right. The motion of the bar 13 toward the right is transmitted to the switch points 2 and 2^a through the end 10^a of the housing 10, sleeve 8, spring 12, sleeve 22, screw jaw 6 and front rod 3, and the switch points are therefore moved from the extreme positions in which they are illustrated in the drawings to their other extreme positions. During this movement of the parts, there is substantially no relative movement between the sleeves 8 and 22 of the spring connecting rod C, and the fulcrum bars 30 and 32 are therefore both rotated in a counterclockwise direction together, as will be apparent from an inspection of the drawings. As a result, the buffering device D is moved to the left as a unit an amount depending upon the proportioning of the parts, and there is no relative movement between the piston 38 and the casing 35. It will be apparent, therefore, that under these conditions, the buffering device D offers no opposition to the movement of the switch points from one extreme position to the other.

If after the switch has been reversed, it is desired to restore the switch to the position in which it is illustrated in the drawings, the switch throwing lever 20 is returned to the position shown. Under these conditions, the operation of the apparatus is just the reverse of that described hereinbefore, as will be apparent from an inspection of the drawings, so that the parts are all restored to the positions in which they are illustrated in Fig. 1. It should be pointed out that under these conditions also, there is no relative movement between piston 38 of buffering device D and casing 35, and that buffering device D does not oppose the movement of the switch points.

If a vehicle trails through the switch when the switch occupies the extreme position in which it is illustrated in the drawings, the vehicle wheels engage the switch point 2 and move the switch points toward the right. Spring rod 7 and sleeve 8 are therefore moved toward the right a like amount, but housing 10 and sleeve 22 are held stationary by switch operating device B. Spring 12 therefore becomes compressed, and exerts a force on the switch points which tends to restore the switch points to their initial positions. When sleeve 8 is moved toward the right, fulcrum bar 30 is rotated in a counterclockwise direction about pivot pin 29, so that casing 35 of buffering device D is moved toward the left, but piston 38 of buffering device D is held fixed under these conditions, because sleeve 22 holds fulcrum bar 32 in the position shown. As a result, the fluid in cylinder 35^a on the right-hand side of piston 38 flows through leak groove 35^b into cylinder 35^a on the left-hand side of piston 38 until casing 35 has moved to the left far enough so that the right-hand

end of leak groove 35^b is past the right-hand side of piston 38, whereupon the pressure of the fluid in cylinder 35^a on the right-hand side of piston 38 opens valve 41 and permits fluid to flow through the holes 38^a in piston 38 into cylinder 35^a on the left-hand side of piston 38. The pressure exerted on valve 41 by spring 44 is comparatively small, so that very little pressure is required to open valve 41. It will be apparent, therefore, that very little force is required to move casing 35 of buffering device D toward the left under these conditions, so that the resistance offered by buffering device D to the movement of the switch points away from their initial positions is very slight. As soon as spring 12 starts to return the switch points to their initial positions, however, sleeve 8 is moved toward the left, and casing 35 is moved toward the right. Piston 38 is still held fixed, and spring 44 now closes valve 41, so that fluid can not pass this valve. Furthermore, since the right-hand end of leak groove 35^b is now to the left of the right-hand side of piston 38, fluid is also prevented from flowing past the piston through leak groove 35^b and, as a result, the rate at which the switch points can return to their initial positions is limited to the rate at which the fluid in cylinder 35^a on the left-hand side of piston 38 can flow through regulating valve 47, until casing 35 has moved toward the right far enough to permit fluid to flow through leak groove 35^b past the piston 38. The rate at which fluid can flow through regulating valve 47 may be varied by turning the valve 47 to change the orifice 47^a which is in registration with port 48, and this rate will usually be adjusted to such a value that the switch points will not return to their initial positions until a time interval has elapsed which is longer than the time interval required for adjacent trucks of a vehicle to pass the switch points when the vehicle is moving at its usual speed.

When the switch points have returned toward their original positions far enough to cause the leak groove 35^b in cylinder 35 to be uncovered by the piston 38, the opposition offered by the device D to the return movement of the switch points is materially decreased and it is therefore apparent that with my invention the first part of the return stroke of the points is materially retarded, while the latter portion of this return stroke is substantially unopposed.

If the switch occupies its other extreme position and a vehicle trails through the switch, the parts will function in a manner similar to that just described but, under these conditions, casing 35 of buffering device D will be held stationary and piston 38 will be moved. This operation of the parts will be readily understood from an inspection of the drawings.

It will be apparent, therefore, that with apparatus embodying my invention substan-

tially no opposition is offered by the buffing device to normal manual operation of the switch or to movement of the switch points away from either extreme position by a trailing railway vehicle, but the return movement of the points after a trailing move is retarded to a degree which can be accurately controlled by valve 47.

One advantage of apparatus embodying 10 my invention is that due to the method of supporting the buffing device D no heavy load is applied to the spring connecting rod C.

Although I have herein shown and described only one form of apparatus embodying 15 my invention, it is understood that various changes and modifications may be made therein within the scope of the appended claims without departing from the spirit and scope of my invention.

20 Having thus described my invention, what I claim is:

1. The combination, with a railway switch comprising a switch point movable between two extreme positions and an operating device 25 connected with said switch point through resilient means for moving said switch point to either of said extreme positions, of a cylinder containing a reciprocable piston, link work for connecting said cylinder and said piston with said resilient means in such manner as to permit relative movement of said piston and said cylinder when said switch point is trailed through by a vehicle but not when said switch point is operated by said device, and means for permitting free relative movement of said piston and said cylinder in one direction and for retarding relative movement of said piston and said cylinder in the opposite direction.

40 2. The combination, with a railway switch comprising a switch point movable between two extreme positions and an operating device connected with said switch point through resilient means for moving said switch point to either of said extreme positions, of a buffing device comprising a casing provided with a cylinder containing fluid, a reciprocable piston in said cylinder, a piston rod extending into said cylinder and attached to said piston, a valve in said piston arranged to permit the flow of fluid through said piston in one direction, and a variable by-pass around said piston; and means for connecting said casing and said piston rod with said resilient means in such manner as to permit relative movement of said piston and said cylinder when said switch point is displaced from an extreme position by a vehicle but not when said switch point is operated by said device.

55 3. The combination, with a railway switch comprising a switch point movable between two extreme positions and an operating device connected with said switch point through resilient means for moving said switch point

to either of said extreme positions, of a buffing device comprising a casing provided with a cylinder containing fluid, a reciprocable piston in said cylinder, a piston rod extending into said cylinder and attached to said piston, means for permitting fluid to flow past said piston for a portion of its stroke, a valve in said piston arranged to permit the flow of fluid through said piston in one direction, and a variable by-pass around said piston; and means for connecting said casing and said piston rod with said resilient means in such manner as to permit relative movement of said piston and said cylinder when said switch point is displaced from an extreme position by a vehicle.

4. The combination, with a railway switch comprising a switch point movable between two extreme positions and an operating device connected with said switch point through resilient means for moving said switch point to either of said extreme positions, of a buffing device comprising a casing provided with a cylinder containing fluid, a reciprocable piston in said cylinder, a piston rod extending into said cylinder and attached to said piston, means at one end of said cylinder for permitting fluid to flow past said piston during a portion of its stroke, a valve in said piston arranged to permit the flow of fluid through said piston in one direction, and a variable by-pass around said piston; and means for connecting said casing and said piston rod with said resilient means to cause relative movement of said piston and said cylinder when said switch point is displaced from an extreme position by a vehicle but not when said switch point is operated by said device.

5. The combination, with a railway switch comprising a switch point movable between two extreme positions and an operating device connected with said switch point through resilient means for moving said switch point to either of said extreme positions, of a buffing device comprising a casing provided with a cylinder containing a fluid, a reciprocable piston in said cylinder, a piston rod extending into said cylinder and attached to said piston for reciprocating said piston, said cylinder being provided at one end with a leak groove to permit fluid to flow around said piston for a portion of its stroke, a valve in said piston arranged to permit the flow of fluid through said piston in one direction, and a variable by-pass around said piston; and means for connecting said casing and said piston rod with said resilient means to cause relative movement of said piston and said cylinder when said switch point is displaced from an extreme position by a vehicle but not when said switch point is operated by said device.

6. In combination, a railway switch movable between two extreme positions, a switch

operating device, a connecting rod for connecting said switch operating device with said switch, said connecting rod including a spring and two movable sleeves so arranged that if said switch is moved to either extreme position by said switch operating device said sleeves will remain in fixed relation with respect to each other but that if said switch is trailed through in an extreme position said sleeves will move relatively to each other and stress said spring to permit movement of said switch, two fulcrum bars each having one end pivotally connected with one of said sleeves, a fixed post, two links each having one end pivoted on said post and having the other end pivotally connected with one of said fulcrum bars intermediate its ends, and a buffering device pivotally connected between the free ends of said fulcrum bar and arranged to permit free relative movement of said sleeves in one direction but to retard relative movement of said sleeves in the opposite direction.

7. In combination, a railway switch movable between two extreme positions, a switch operating device, a connecting rod for connecting said switch operating device with said switch, said connecting rod including a spring and two movable sleeves so arranged that if said switch is moved to either extreme position by said switch operating device said sleeves will remain in fixed relation with respect to each other but that if said switch is trailed through in an extreme position said sleeves will move relatively to each other and stress said spring to permit movement of said switch, two fulcrum bars each having one end pivotally connected with one of said sleeves, a fixed post, two links each having one end pivoted on said post and having the other end pivotally connected with one of said fulcrum bars intermediate its ends; a buffering device comprising a casing provided with a cylinder containing a fluid, a reciprocable piston in said cylinder, a piston rod extending into said cylinder and attached to said piston for reciprocating said piston, a valve in said piston arranged to permit the flow of fluid through said piston in one direction, and a by-pass around said piston including a valve for regulating the flow of fluid through said by-pass, means for pivotally connecting said casing to the free end of one of said fulcrum bars, and means for pivotally connecting said piston rod with the free end of the other said fulcrum bar.

8. In combination, a railway switch movable between two extreme positions, a switch operating device, a connecting rod for connecting said switch operating device with said switch, said connecting rod including a spring and two movable sleeves so arranged that if said switch is moved to either extreme position by said switch operating device said sleeves will remain in fixed relation with respect to each other but that if said switch is trailed through in an extreme position said sleeves will move relatively to each other and stress said spring to permit movement of said switch, two fulcrum bars each having one end pivotally connected with one of said sleeves, a fixed post, two links each having one end pivoted on said post and having the

other end pivotally connected with one of said fulcrum bars intermediate its ends; a buffering device comprising a casing provided with a cylinder containing a fluid, a reciprocable piston in said cylinder, a piston rod extending into said cylinder and attached to said piston for reciprocating said piston, a valve in said piston arranged to permit the flow of fluid through said piston in one direction, and a variable by-pass around said piston; means for pivotally connecting said casing to the free end of one of said fulcrum bars, and means for pivotally connecting said piston rod with the free end of the other said fulcrum bar.

9. In combination, a railway switch movable between two extreme positions, a switch operating device, a connecting rod for connecting said switch operating device with said switch, said connecting rod including a spring and two movable sleeves so arranged that if said switch is moved to either extreme position by said switch operating device said sleeves will remain in fixed relation with respect to each other but that if said switch is trailed through in an extreme position said sleeves will move relatively to each other and stress said spring to permit movement of said switch, two fulcrum bars each having one end pivotally connected with one of said sleeves, a fixed post, two links each having one end pivoted on said post and having the other end pivotally connected with one of said fulcrum bars intermediate its ends; a buffering device comprising a casing provided with a cylinder containing a fluid, a reciprocable piston in said cylinder, a piston rod extending into said cylinder and attached to said piston for reciprocating said piston, a valve in said piston arranged to permit the flow of fluid through said piston in one direction, and a by-pass around said piston including a valve for regulating the flow of fluid through said by-pass, means for pivotally connecting said casing to the free end of one of said fulcrum bars, and means for pivotally connecting said piston rod with the free end of the other said fulcrum bar.

10. In combination, a railway switch movable between two extreme positions, a switch operating device, a spring connecting rod for connecting said switch operating device with said switch, said connecting rod including a spring and two movable sleeves so arranged that if said switch is moved to either extreme position by said operating device said sleeves will move together but that if said switch is trailed through in one extreme position one of said sleeves will be held fixed and the other will move toward said one sleeve and compress said spring to permit movement of the switch away from said one extreme position and that if said switch is trailed through in the other extreme position said other sleeve will be held fixed and said one

- sleeve will move toward said other sleeve and compress said spring to permit movement of the switch away from said other extreme position, two fulcrum bars each having one end pivotally connected with one of said sleeves, a fixed post, two links each having one end pivoted on said post and having the other end pivotally connected with one of said fulcrum bars intermediate its ends, 5
10 a buffering device comprising a casing provided with a cylinder containing a fluid, a reciprocable piston in said cylinder, a piston rod extending into said cylinder and attached to said piston for reciprocating said piston, 15 a valve in said piston arranged to permit the flow of fluid through said piston in one direction, and a by-pass around said piston including one or more restricted orifices, means for pivotally connecting said casing to the free 20 end of one of said fulcrum bars, and means for pivotally connecting said piston rod with the free end of the other said fulcrum bar.
11. In combination, a railway switch having switch points movable between two extreme positions, a switch operating device; a spring connecting rod comprising a housing connected with said switch operating device and provided with aligned openings, two sleeves, one arranged to slide freely in each of 25 said openings and each having an integral flange located on the inside of said housing and adapted to at times engage the inside of said housing adjacent said openings, a spring in said housing arranged to urge said sleeves 30 to the positions in which said flanges engage said housing, and a spring rod extending freely through said spring and said sleeves and connected at one end with the switch points and provided with means for at times 35 engaging one or the other of said sleeves at its outer end; two fulcrum bars each having one end pivotally connected with one of said sleeves, a fixed post, two links each having one end pivoted on said post and having the other end pivotally connected with one of 40 said fulcrum bars intermediate its ends, and a buffering device pivotally connected between the free ends of said fulcrum bars.
12. In combination, a railway switch having switch points movable between two extreme positions, a switch operating device; a spring connecting rod comprising a housing connected with said switch operating device and provided with aligned openings, two 45 sleeves, one arranged to slide freely in each of said openings and each having an integral flange located on the inside of said housing and adapted to at times engage the inside of said housing adjacent said openings, a spring in said housing arranged to urge said sleeves toward the positions in which said flanges engage said housing, and a spring rod extending freely through said spring and said sleeves and connected at one end with the switch 50 points and provided with means for at times

engaging one or the other of said sleeves at its outer end; two fulcrum bars each having one end pivotally connected with one of said sleeves, a fixed post, two links each having one end pivoted on said post and having the other end pivotally connected with one of said fulcrum bars intermediate its ends, a buffering device comprising a casing provided with a cylinder containing a fluid, a reciprocable piston in said cylinder, a piston rod extending into said cylinder and attached to said piston for reciprocating said piston, a valve in said piston arranged to permit the flow of fluid through said piston in one direction, and a by-pass around said piston including a restricted orifice; means for pivotally connecting said casing to the free end of one of said fulcrum bars, and means for pivotally connecting said piston rod with the free end of the other said fulcrum bar.

13. In combination, a railway switch movable between two extreme positions, a switch operating device, a spring connecting rod for connecting said switch operating device with said switch, said connecting rod including a spring and two movable sleeves so arranged that if said switch is moved to either extreme position by said operating device said sleeves will move together but that if said switch is trailed through in one extreme position one of said sleeves will be held fixed and the other will move toward said one sleeve and compress said spring to permit movement of the switch away from said one extreme position and that if said switch is trailed through in the other extreme position said other sleeve will be held fixed and said one sleeve will move toward said other sleeve and compress said spring to permit movement of the switch away from said other extreme position, two fulcrum bars each having one end pivotally connected with one of said sleeves, a fixed post, two links each having one end pivoted on said post and having the other end pivotally connected with one of said fulcrum bars intermediate its ends, a buffering device comprising a casing provided with a cylinder containing a fluid, a reciprocable piston in said cylinder, a piston rod extending into said cylinder and attached to said piston for reciprocating said piston, said cylinder being provided at one end with a leak groove to permit fluid to flow around said piston for a portion of its stroke, a valve in said piston arranged to permit the flow of fluid through said piston in one direction, and a by-pass around said piston including a restricted orifice, means for pivotally connecting said casing to the free end of one of said fulcrum bars, and means for pivotally connecting said piston rod with the free end of the other said fulcrum bar.

In testimony whereof I affix my signature.
WILLIAM C. McWHIRTER.
